UNITED STATES PATENT OFFICE

120,776

DESIGN FOR A VACATION HOUSE

William C. Callaway, Pasadena, Calif.

Application March 4, 1940, Serial No. 90,655

Term of patent 7 years

To all whom it may concern:

Be it known that I, William C. Callaway, a citizen of the United States and residing at Pasadena, in the county of Los Angeles and State of California, have invented a new, original, and ornamental Design for a Vacation House, of which the following is a specification, reference being had to the accompanying drawings, forming a part thereof.

In the accompanying drawings.

Fig. 1 is a top plan view on a reduced scale of a vacation house showing my new design;

Fig. 2 is a side elevational view of the house, looking in the direction indicated by the arrow 2 in Fig. 1;

Fig. 3 is a side elevational view of the house, looking in the direction indicated by the arrow 3 in Fig. 1;

Fig. 4 is a plan view of the base member only, looking in the direction of the arrows 4-4 on Fig. 2;

Fig. 5 is a side elevational view of the house looking in the direction indicated by the arrow 5 in Fig. 1; and

Fig. 6 is a side elevational view of the house looking in the direction indicated by the arrow 6 in Fig. 1.

I claim:

The ornamental design for a vacation house, substantially as shown.

WILLIAM C. CALLAWAY.
